United States Patent Office

Des. 221,387
Patented Aug. 10, 1971

221,387

LIQUID DISPENSER

Louise E. Bacon, North Canton, and Siegfried Garbe, Canton, Ohio, assignors to Spartan International Corporation, Glendale, N.Y.

Filed Nov. 24, 1969, Ser. No. 20,239

Term of patent 14 years

Int. Cl. D6—01

U.S. Cl. D33—30

Fig. 3

FIG. 1 is a perspective view of a liquid dispenser showing our new design;

FIG. 2 is a side elevational view thereof;

FIG. 3 is a front elevational view thereof; and

FIG. 4 is a top plan view thereof.

We claim:

The ornamental design for a liquid dispenser, as shown.
